Irving J. Hopfenberg, New York, N. Y., assignor
to Freeman Daughaday Company, Providence,
R. I., a corporation of Massachusetts

Application November 29, 1937, Serial No. 73,241

Term of patent 14 years

To all whom it may concern:

Be it known that I, Irving J. Hopfenberg, a citizen of the United States, residing at 1203 Frisco Ave., Far Rockaway, New York, in the county of Queens and State of New York, have invented a new, original, and ornamental Design for a Collar Holder, of which the following is a specification, reference being had to the accompanying drawing, forming part thereof.

In the drawing:

Fig. 1 is a side view of a collar holder showing my new design;

Fig. 2 is a top view thereof; and

Fig. 3 is a bottom view thereof.

I claim:

The ornamental design for a collar holder as shown.

IRVING J. HOPFENBERG.
